AIR CYLINDER APPARATUS FOR BOTTLE
FILLING MACHINESGeorge J. Meyer, Milwaukee, Wis., assignor to
Geo. J. Meyer Manufacturing Company, Cudahy, Wis., a corporation of Wisconsin

Application July 20, 1940, Serial No. 346,563

7 Claims. (Cl. 121—45)

The present invention relates to bottle filling machines and more particularly to the cylinder apparatus for the type of filling machine in which the bottles are lifted to filling position by fluid pressure, a machine of this general type being exemplified in United States Letters Patent No. 1,166,520 to John E. Henes, dated January 4, 1916.

An object of the invention is to provide the bottle lifting cylinders of a filling machine with improved valve means of simple and durable construction for controlling their operation, the valve means being capable of inexpensive manufacture and being of such character as to permit easy and accurate resurfacing of the cooperating valve seats or faces thereof if accidentally damaged by foreign substances.

Another object is to provide simple and easily mounted means for supplying compressed air or other motive fluid to the several valve-controlled cylinders.

Still another object is to perfect details of construction generally.

The invention further consists in the several features hereinafter described and claimed.

In the accompanying drawings,

Fig. 1 is a partial vertical sectional elevation of a bottle filling machine embodying the invention, the section being taken generally along the line 1—1 of Fig. 2;

Fig. 2 is a partial plan and horizontal section;

Fig. 3 is a bottom view of a portion of an air cylinder assembly, parts being broken away, parts being shown in section, and parts being omitted;

Fig. 4 is a sectional elevation of the lower portion of one of the cylinders, taken transversely of its path of movement, a bottle-lifting piston for the cylinder being shown in its lowermost position;

Fig. 5 is an outer elevation of the cylinder assembly of Fig. 3, parts being broken away and parts being shown in section;

Fig. 6 is a sectional elevation taken generally along the line 6—6 of Fig. 5;

Fig. 7 is a top view of a rocking valve member;

Fig. 8 is a perspective view of a centering ring for the valve member;

Fig. 9 is a top view of a cup leather retainer, and

Fig. 10 is a sectional elevation of the cup leather retainer, taken along the line 10—10 of Fig. 9, a portion of a cooperating piston member being also shown in section.

In these drawings, 15 designates a base plate on which is mounted a legged stand 16, Fig. 2, having a tubular post or column 17, and 18 designates a

wheel or carrier which is rotatably mounted on the tubular post. The usual tank or bowl 19 is suitably supported above the wheel 18 to rotate therewith, and is adapted to contain and distribute the liquid to be bottled, the tank being supplied with liquid through the usual pipe 20, Fig. 2, extending concentrically through the tubular post 17. The tank is provided with the usual downwardly projecting filling nozzles or siphon tubes 21, one being shown, and is further provided with pivoted bottle-centering guides 22, one being shown.

Below and in line with the siphon tubes 21, vertical cylinders 23 are rigidly secured near their upper ends on the apertured rim portion of the wheel 18, so as to turn with the wheel and tank. These cylinders are arranged in a circular series as usual and are provided with pistons designated generally by the numeral 24, and hereinafter more fully described. The pistons are attached to piston rods 25 which are provided at their upper ends with supports or platforms 26 on which the bottles 27 are adapted to stand. Each piston rod is preferably of square or other noncircular cross-section and slidably extends through an upper cylinder head 28. This cylinder head has a relief port 29 which is open at all times to the space above the piston. Each piston may be individually locked in its lowermost position, as by means of a detachable pin 30, Fig. 1, adapted to pass through transversely extending apertures 31 in the piston rod and the upper cylinder head.

The lower ends of the cylinders 23 are secured to bottom cylinder heads 32 which also form valve bodies, there being a double cylinder head for each adjacent pair of cylinders. Formed on the underside of each head 32 are two generally circular valve seat embossments 33, one for each of the two cylinders, each embossment being eccentrically arranged with respect to the axis of the corresponding cylinder. These embossments present flat annular valve seats 34 which are disposed in a plane normal to the cylinder axes, there being a central recess 35 in each embossment. A vertical bore 36 extends in each embossment coaxially of the cylinder and communicates with the cylinder space to form an exhaust port, the upper end of this bore presenting a conical valve seat 37, Fig. 4. A straight inclined bore 38 in the cylinder head has its lower end forming a port in the valve seat 34 at a point diametrically opposite the lower end of the bore 36. The inclined bore extends along a rib 39 of a projection or ear 40 formed at the inner side of the bottom cylinder head radially of the wheel and communicates

50 55

with a pocket 41 in an upwardly opening semi-cylindrical header seat 42 formed transversely of the ear. Each rib extends radially from the periphery of the corresponding valve seat embossment. A horizontal ring-like air supply tube 43 forming a header or manifold is arranged concentrically of the wheel 18 and is secured to the seats 42 by clamps 44 which are fastened to the ears 40 by bolts 45. The tubular header 43 is provided at its bottom with ports 46, Fig. 4, registering with the pockets 41, and apertured packing members 47 of leather or other suitable material are interposed between the header and the semi-cylindrical seats 42. Compressed air is conducted to the header 43 by a pipe 48, and the latter communicates with a source of compressed air through the usual swivel coupling, not shown. An inlet port or bore 49 is formed in each cylinder head embossment 33 at a distance from the supply port 38 and communicates with the cylinder space.

An oscillatory or rocking valve member 50, bearing against the valve seat 34 of each cylinder, controls the admission and release of air or other motive fluid under pressure to and from the cylinder, so as to effect the raising and lowering of the bottle with respect to the filling nozzle or siphon tube 21. Each valve member 50 is provided with a flat annular valve seat 51 and a central recess 52. A ring 53 in the form of a short tube fits around the cylinder head embossment 33 and the registering circular portion or embossment 54 of the valve member to retain the valve member in a centered position with respect to the cylinder head embossment, and to form a pivot means, the ring being confined axially by the bottom of the cylinder head and by a peripheral flange 55 formed on the valve member. The centering ring 53 is engageable with spaced lands 56, Fig. 3, formed on the periphery of the cylinder head embossment 33, and is provided with a notch 57, Fig. 8, which provides clearance for the cylinder head rib 39 and prevents rotation of the ring. The ring 53 also encloses the joint at the peripheries of the valve seat and the valve member face. The axial width of the ring 53 is somewhat shorter than the distance between the bottom of the cylinder end wall and the valve member flange 55, so as to allow for wear of the valve. An arcuate transfer port or pocket 58 is formed in the valve seat or face 51 of the valve member and is adapted to communicate with the air supply bore 38 and cylinder inlet port 49, so as to admit compressed air into the cylinder when the valve member is swung to one of its terminal positions. An exhaust port or passage 59 extends through the valve member and is adapted to communicate with the cylinder head exhaust port 36 when the valve member is swung to its other terminal position.

Each valve member 50 is urged upwardly against the ported seat 34 of the cylinder head valve embossment 33 by a compressed coil spring 60 of conical shape, the enlarged lower end of the spring resting on the apertured bottom wall of a bracket or cage 61 secured below the cylinder head, and the reduced upper end of the spring fitting over the shank of a rivet 62, the round head of which bears in a conical pocket 63 formed centrally in the bottom face of the valve member. The bracket 61 is provided with upwardly projecting end lugs 64 and an intermediate lug 65 bearing against the flat bottom faces of downwardly projecting lugs 66 and 67 formed

on the double cylinder head 32, the registering end lugs 64 and 66 being secured together by bolts 68, and the registering intermediate lugs 65 and 67 being secured together by a bolt 69. The bottom faces of the lugs 66 and 67 are coplanar with the bottom faces of the valve seat embossments, thus facilitating machining. Each rocking valve member 50 has formed thereon a pair of angularly related operating arms 70 and 71 which extend in generally opposite directions and are near the projected plane of the flat valve face, the sides of the bracket 61 being open to afford clearance for these arms. The bracket is provided at its opposite sides with upstanding stop abutments or lugs 72 and 73 which are adapted to be engaged by the arms of the valve members to limit the angular movement of the valve members and to determine the terminal positions of these members. The inwardly projecting arms 70 are engageable with the stop lugs 72, while the outwardly projecting arms 71 are engageable with the stop lugs 73. The arms are engageable alternately with trips 74 and 75 to turn the valve member first in one direction to admit air to the cylinder and then in the opposite direction to exhaust air from the cylinder. These trips are preferably in the form of rollers, to reduce friction and wear and are adjustably mounted on a stationary curved bar 76 secured to the stand 16 and arranged concentrically of the wheel 18. The trip 74, which controls the raising of the pistons, is engageable with the inwardly projecting valve member arms 70, while the trip 75, which controls the lowering of the pistons, is engageable with the outwardly projecting valve member arms 71. The rocking valve members are suitably lubricated, as by admitting a small quantity of water into the air supply pipe 48. The water will drain out of the bottom ports 46 of the header 43 and down the inclined passages 38 to the valve members.

The bottle-carrying wheel 18 and the tank 19 are rotated in any suitable manner, as by means of gearing including a ring gear 77 secured to the underside of the wheel.

On one side of the machine between the trips 74 and 75 the filled bottles are discharged from the machine onto a table 78, as by means of a curved diverting guide 79.

Each piston 24 comprises a piston member 80 which is held on the reduced lower portion of the piston rod 25 against relative rotation and has a dished bottom surface 81, the marginal portion of which is defined by a downwardly projecting annular rib 82 having a concave inner surface. An annular retaining member 83 of thin soft sheet metal, such as brass, has curved marginal portions 84 to fit within the annular piston rib 82 and against the bottom of the piston member, and has a tapered lower edge 85, Fig. 10, adapted to slidably bear against the cylinder walls. The piston member 80 and retaining member 83 have approximately equal outside diameters. A cupped packing member 86, such as a cup leather, is clamped against the bottom of the piston member 80 and retaining ring 85 by a cylindrical follower 87 which is screw-threaded onto the lower end of the piston rod 25. The outer bend of the leather fits against the concave inner surface of the retaining ring 83. The outer diameter of the follower is slightly smaller than the inner diameter of the cup leather, and the upper circular margin 88 of the follower is slightly rounded to fit against the inner bend of the leather. The radius of the bend in the concave peripheral por-

tion of the retaining ring 83 is slightly greater than the thickness of the leather, and the free edge of the leather bears against the cylinder walls below the thin lower edge of the retaining ring. By this construction the cup leather is firmly confined in position, and the shape of the cup leather is maintained. The retaining ring 83 avoids the formation of a shoulder at the peripheral portion of the cup leather and prevents any tendency of the leather to squeeze between the cylinder walls and the piston walls.

In order to cushion the movement of the piston at the lower end of its descending travel, a headed needle valve 89 is slidably mounted and loosely confined in aligned vertical bores 90 and 91 formed in the lower ends of the piston rod and follower and has a flattened or fluted conical lower end adapted to engage the conical valve seat 37 at the upper end of the exhaust port 36, thus restricting the outflow of air. The headed upper end of the needle valve prevents the valve from dropping out when the piston is raised.

In operation, the bottle-carrying wheel 18 and liquid tank 19 rotate in the direction indicated by the arrow in Fig. 2. The bottle supports 26 in the vicinity of the discharge table 18 are in their lower positions, and empty bottles are placed on the supports as they pass between the discharge table and the trip 74. When the inwardly projecting arms 70 on the rocking valve members 50 pass the trip roller 74, they turn the valve members into the position shown in Fig. 5 and shown by dotted lines in Fig. 3, thus closing the exhaust ports 36 in the lower cylinder heads and admitting air to the inlet ports 49 by way of the arcuate transfer ports or pockets 58, so as to force the pistons upwardly, carrying the bottles on the supports 26 upwardly beyond the displaceable centering guides 22 and over the siphon tubes 21. The moving bottles are then filled with liquid in the manner characteristic of counter-pressure filling machines. After the bottles are filled the outwardly projecting arms 71 of the valve members are brought into engagement with the trip 75, thus turning the valve member 50 to the position seen in Fig. 4 and shown by full lines in Fig. 3, shutting off the supply of compressed air to the cylinders and opening the cylinder exhaust ports 36. The pistons 25 with the filled bottles carried by the supports 26 are thus allowed to descend by gravity, and the lower portion of their travel is cushioned by the operation of the cushioning valves 89. The filled bottles finally reach the diverting guide 19 and pass onto the discharge table 18.

In a filling machine, a bottle-lifting cylinder or its associated siphon may occasionally get out of order, and it may not be convenient to stop the machine for some time thereafter to permit adjustment. While individual air cocks for the cylinders could be provided to shut off the air supply in such contingency, it is somewhat simpler to retain a piston in its lowermost position by the detachable locking pin 30 shown in Fig. 1.

In some instances, foreign substances may damage the flat polished faces 34 and 51 of the valve seat embossments 33 and the rocking valve members 50. If this should occur, the brackets 61 can readily be detached from the lower cylinder heads to permit removal of the valve members and their centering rings, and the flat valve faces on the embossments and valve members can easily be lapped back to proper condition, as by means of an abrasive disk, there being no

pivot means or other projections to interfere with this operation.

What I claim as new and desire to secure by Letters Patent is:

5. In combination, a cylinder having a piston therein and having an embossment presenting a flat valve seat ported to communicate with the cylinder space, said cylinder having a rib extending laterally from the periphery of said embossment and having in said rib a fluid supply passage forming a port at said seat, a rocking valve member having a flat ported valve face engageable with said valve seat for controlling the flow of fluid with respect to said cylinder, means for detachably holding said valve member against said seat, and an annular centering member for said rocking valve member fitting around the engaging portions of said valve seat and valve face and having a notch through which said rib extends.
10. In combination, a cylinder having a piston therein and having an embossment with a flat valve seat ported to communicate with the cylinder space, a rocking valve member having a flat ported valve face engageable with said valve seat for controlling the flow of fluid with respect to said cylinder, means for detachably holding said valve member against said seat, and an annular centering member for said rocking valve member fitting around the engaging portions of said valve seat and valve face, said centering member being stationary with respect to said valve seat and being confined axially by a peripheral portion of said valve member.
15. In combination, a cylinder having a piston therein and having an embossment with a flat valve seat thereon ported to communicate with the cylinder space, a rocking valve member having an embossment with a flat ported valve face thereon engageable with said valve seat for controlling the flow of fluid with respect to said cylinder, means for detachably holding said valve member against said seat, and an annular centering member for said valve member detachably fitting around said valve seat embossment and said valve member embossment, said valve member having a projection to axially confine said annular centering member.
20. In combination, a cylinder having a piston therein and having a flat valve seat ported to communicate with the cylinder space and with a source of motive fluid, a rockably mounted disk valve member having a flat ported valve face engageable with said valve seat for controlling the flow of fluid with respect to said cylinder, said valve member having a pair of angularly spaced operating arms extending outwardly from its periphery, a bracket secured to said cylinder and being open at opposite sides to pass said respective arms, and spring means carried by said bracket for holding said valve member against said seat.
25. In combination, a cylinder having a piston therein and having a flat valve seat ported to communicate with the cylinder space and with a source of motive fluid, a rockably mounted armed valve member having a flat ported valve face engageable with said valve seat for controlling the flow of fluid with respect to said cylinder, a bracket having lugs secured to said cylinder, and spring means carried by said bracket for holding said valve member against said seat, said cylinder having bracket-attaching projections presenting surfaces coplanar with said
30. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
35. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
40. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
45. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
50. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
55. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
60. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
65. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
70. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said
75. In combination, a cylinder having a piston therein and having a flat valve seat ported to communicate with the cylinder space and with a source of motive fluid, a rockably mounted valve member having a flat ported valve face engageable with said valve seat for controlling the flow of fluid with respect to said cylinder, a bracket secured to said cylinder and being open at opposite sides to pass said respective arms, and spring means carried by said bracket for holding said valve member against said seat, said cylinder having bracket-attaching projections presenting surfaces coplanar with said

valve seat and forming abutments for the ends of said lugs.

6. In combination, a cylinder having a piston therein and having a head provided with a flat exterior valve seat and a conduit seat, said valve seat being at the end of the cylinder and said conduit seat being at the side of the cylinder, there being a straight bore in said head connecting said seats and forming a port at said valve seat, said bore extending at an angle to the plane of said valve seat, said valve seat being ported to communicate with the cylinder space, a ported fluid supply conduit clamped to said conduit seat and communicating with said bore, and a rocking valve member having an operative engage-

ment with said ported valve seat for controlling the flow of fluid with respect to said cylinder.

7. In combination, a valve body having thereon an embossment with a flat valve seat ported for the passage of fluid, a rocking valve member having a flat valve face engageable with said valve seat for controlling the flow of fluid, means for detachably holding said valve member against said seat, and an annular centering member for 10 said rocking valve member, detachably fitting around said valve seat embossment and the face portion of said valve member, said valve member having a peripheral portion axially confining said centering member.

GEORGE J. MEYER.
